UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS LIMITED, OF WESTMINSTER, LONDON, ENGLAND.

ORDNANCE.

1,364,546.

Specification of Letters Patent.

Patented Jan. 4, 1921.

Application filed December 18, 1919. Serial No. 345,907.

To all whom it may concern:

Be it known that we, Sir ARTHUR TREVOR DAWSON, knight, and Sir GEORGE THOMAS BUCKHAM, knight, both subjects of the King 5 of Great Britain, residing at Vickers House, Broadway, Westmister, in the county of London, England, have invented certain new and useful Improvements in or Relating to Ordnance, of which the following is a 10 specification.

This invention relates to ordnance provided with vertical deflection gear for adding or subtracting the vertical deflection angle to or from the angle of tangent elevation for a target advancing toward or receding from the gun position; the invention is 15 particularly applicable to such guns having an independent line of sight.

According to the invention we provide 20 means whereby the operation of the vertical deflection gear causes the reading of the tangent elevation or range indicator operated by the tangent elevation or ranging gear which effects relative movement between the gun and the sight, to be varied by 25 an amount proportionate to the amount of the vertical deflection it is required to impart so that the act of operating the tangent elevation or ranging gear until the 30 reading of the indicator is the same as it was prior to the operation of the vertical deflection gear, imparts the required vertical deflection. For this purpose the vertical deflection gear and the tangent elevation or 35 ranging gear may operate upon the usual tangent elevation dial through a differential gear so that the dial can be operated either simultaneously or independently by the said gears.

In order that the said invention may be 40 clearly understood and readily carried into effect, we will describe the same more fully with reference to the accompanying drawings, in which:—

Figure 1 is a perspective view showing 45 diagrammatically a gun carriage for a gun having an independent line of sight, provided with a form of our improvements.

Fig. 2 is a vertical transverse section 50 showing a constructional form of the improvements illustrated diagrammatically in Fig. 1.

Fig. 3 is an elevation showing a slightly 55 modified arrangement of the tangent elevation dial and the differential gear through

which this dial is operated by the vertical deflection gear and the tangent elevation gear,

Fig. 4 is a section taken approximately on the line 4—4 of Fig. 3, and 60

Figs. 5 and 6 are respectively a side elevation and a plan showing diagrammatically the invention employed in conjunction with a gun not having an independent line of sight. 65

In Figs. 1 to 4 A is the tangent elevation dial and A' is the zero or index mark against which the graduations on the dial are read. B is a shaft operated by the tangent elevation hand wheel B' through the 70 gearing shown by Fig. 2, this gearing comprising a worm b driven from the hand-wheel B' through gear wheels which are not shown, a worm wheel b' a bevel wheel b^x and a bevel pinion b^x. C is a shaft operated by 75 the hand-wheel C' of the vertical deflection gear (Fig. 2) which is situated at the right hand side of the carriage. These shafts B and C operate upon the dial through the differential gear D which is associated with 80 the said shafts and with the dial A either in the manner shown by Fig. 2 or in that shown by Fig. 3. A spring E of the spiral or clock type is in Fig. 3 interposed between the casing D' of the differential gear and 85 the member D² of this gear attached to the dial A, this spring tending to move the dial constantly in one direction for the purpose of eliminating backlash in the geared members of the differential gear. 90

The pointing crankhandle F of the gun is geared direct to the sight bracket through the shafts e e', and interposed bevel pinions, and a worm on the shaft e gearing with the sight elevating rack e² as shown by Fig. 1. 95 An extension e^x (Fig. 2) of the shaft e carries a worm meshing with a worm wheel E and between this worm wheel and the aforesaid worm wheel b' is a differential gear which is associated as shown by Fig. 2 with 100 a shaft F^x carrying a pinion F' gearing with the elevating rack F² (Fig. 1). Thus the pointing gear elevates the gun and the sight together while the tangent elevation gear elevates the gun alone by the amount 105 of tangent elevation plus the vertical deflection.

In Figs. 5 and 6 which show the invention employed in conjunction with a gun not having an independent line of sight, G is 110

the sight bracket and G' the toothed arc thereon with which meshes a pinion g . G^2 is the hand wheel which adjusts the sight for range and which operates the pinion g through a differential gear similar to that shown by Figs. 3 and 4; this differential gear is also operated upon by the vertical deflection hand-wheel C' and is associated with the range dial A in substantially the 5 manner described with reference to Figs. 10 3 and 4. Thus when the vertical deflection hand-wheel C' is operated, the reading of the dial A against the zero mark A' is varied by an amount proportionate to the 15 amount of vertical deflection it is desired to impart, with the result that the actuation of the hand-wheel G^2 to cause the reading to be the same as it was previously, imparts the required vertical deflection to the sight 20 bracket G .

What we claim and desire to secure by Letters Patent of the United States is:—

1. In ordnance, the combination with the sight of means for effecting relative movement between the gun and the sight to impart the required angle of tangent elevation, an indicator operated by said means, vertical deflection gear and means whereby the operation of the vertical deflection gear 25 causes the reading of the said indicator to be varied so that the act of operating the first mentioned means until the reading of the indicator is the same as it was prior to the operation of the vertical deflection gear, im- 30 parts the required vertical deflection.

2. In ordnance, the combination with the sight, of means for effecting relative movement between the gun and the sight to impart the required angle of tangent elevation, an indicator operated by said means, vertical deflection gear and differential gear 40 through which said means and said vertical deflection gear operate upon the indicator.

3. In ordnance having an independent line 45 of sight, the combination with the sight, of pointing gear for elevating the gun and the sight together, ranging gear for moving the gun relatively to the sight to give the required angle of tangent elevation, an indi-

cator operated by the ranging gear, vertical 50 deflection gear and means whereby the operation of the vertical deflection gear causes the reading of the said indicator to be varied so that the act of operating the ranging gear until the reading of the indicator is 55 the same as it was prior to the operation of the vertical deflection gear, imparts the required vertical deflection.

4. In ordnance having an independent line of sight, the combination with the sight, of pointing gear for elevating the gun and the sight together, ranging gear for moving the gun relatively to the sight to give the required angle of tangent, differential gear through which the pointing gear and the 60 ranging gear operate upon the gun, an indicator operated by the ranging gear, vertical deflection gear and differential gear through which said ranging gear and said vertical deflection gear operate upon the indicator. 70

5. In ordnance, the combination with the sight, of sight elevating gear for moving the sight relatively to the gun to give the required angle of tangent elevation, an indicator operated by this gear, vertical deflection gear and means whereby the operation of the vertical deflection gear causes the reading of the said indicator to be varied so that the act of operating the sight elevating gear until the reading of the indicator is the same as it was prior to the operation of the vertical deflection gear, im- 75 parts the required vertical deflection.

6. In ordnance the combination with the sight, of sight elevating gear for moving 85 the sight relatively to the gun to give the required angle of tangent elevation, an indicator associated with said sight elevating gear, vertical deflection gear which is associated with said indicator, and differential 90 gear through which said sight elevating gear and said vertical deflection gear operate upon the indicator.

In testimony whereof we affix our signatures.

ARTHUR TREVOR DAWSON.
GEORGE THOMAS BUCKHAM.
